US0D1080657S

(12) United States Design Patent (10) Patent No.: US D1,080,657 S
(45) Date of Patent: * Jun. 24, 2025

(54) DISPLAY SCREEN OR PORTION THEREOF WITH ICON

(71) Applicant: BIMBI WORLDWIDE, S.L., Jesús (ES)

(72) Inventor: Daniel Ramón Costa, Jesús (ES)

(73) Assignee: BIMBI WORLDWIDE, S.L., Jesús (ES)

() Term: 15 Years

(21) Appl. No.: 29/896,837

(22) Filed: Jul. 7, 2023

(30) Foreign Application Priority Data

Jan. 10, 2023 (EM) 015008351-0001

(51) LOC (15) Cl. 14-04

(52) U.S. Cl.

USPC D14/495

(58) Field of Classification Search

USPC D14/485-495

See application file for complete search history.

CLAIM

The ornamental design for a display screen or portion thereof with icon as shown and described.

DESCRIPTION

The patent or application file contains a least one drawing/photograph executed in color. Copies of this patent or patent application publication with color drawing(s)/photograph(s) will be provided by the Office upon request and payment of the necessary fee.

The FIGURE is a front view of a display screen or portion thereof with icon, showing my new design.

The outer broken lines in the FIGURE show the display screen or portion thereof, and form no part of the claimed design.

1 Claim, 1 Drawing Sheet
(1 of 1 Drawing Sheet(s) Filed in Color)
